Inventor:
William G. Moland,
By Jas. C. Nobusmith
Attorney.

UNITED STATES PATENT OFFICE.

WILLIAM G. MOLAND, OF PHILADELPHIA, PENNSYLVANIA.

SHOE-TREE.

Application filed September 25, 1926. Serial No. 137,661.

My invention relates to shoe trees, that is, to a device adapted to be inserted in a shoe for the purpose of stretching and eliminating wrinkles in the same when the shoe is not in use.

The principal objects of my invention are to provide a shoe tree which may be readily and quickly inserted into and removed from a shoe; which is so constructed and arranged 10 that the principal parts of the same may be stamped and formed from sheet metal; which will be strong yet relatively light; which will permit the shoe when in a damp or wet condition to dry out quickly; and which is provided 15 with means whereby the shoe may be hung up out of the way when the shoe tree is placed therein.

The nature and characteristic features of my invention will be more fully understood 20 from the following description, taken in connection with the accompanying drawings forming part hereof, in which:

Fig. 1 is a side elevation of a shoe tree embodying the main features of my invention, 25 the same being shown with the parts in the positions assumed when the device is in operative relationship with a shoe, the shoe being illustrated in dotted lines;

Fig. 2 is a top or plan view of the shoe tree; 30 Fig. 3 is a side elevation of the shoe tree shown in the folded condition;

Fig. 4 is a transverse section of the toe piece, the view being taken on the line 4—4 of Fig. 2;

Fig. 5 is a longitudinal section taken approximately on the line 5—5 of Fig. 1;

Fig. 6 is a transverse section enlarged taken approximately on the line 6—6 of Fig. 5;

Fig. 7 is a longitudinal section of the heel 40 portion, the view being taken approximately on the line 7—7 of Fig. 2;

Fig. 8 is a transverse section taken approximately on the line 8—8 of Fig. 1; and

Fig. 9 is a side elevation of a shoe with 45 the device of my invention mounted therein, the same being shown suspended on a hook secured in a side wall.

Referring to the drawings, in the particular embodiment of my invention therein shown, 50 10 is a toe piece, preferably made of sheet aluminum and shaped to the approximate form of the inside of the front end of a shoe, the same being provided with a plurality of longitudinally extending slots or apertures 55 11, these slots or apertures 11 serving as a

means of ventilation to permit the moisture to evaporate from the inside of the toe portion of the shoe as well as from the outer surface thereof, when the shoe tree is positioned in the shoe. These slots or apertures 11 not only 60 extend longitudinally, but are also arranged in more or less staggered relationship, whereby the wrinkles in the toe portion of the shoe will be more readily eliminated.

The toe piece 10 is also provided at its 65 lower and rear marginal edges with inturned lips 12, which serve not only to strengthen the structure, but also assist in properly positioning the toe piece within the front end of the shoe.

A bracket member 13 is secured by means of rivets 14 to the rear upper portion of the toe piece, and a link member 15 is pivotally secured by means of a rivet 16 to said bracket member 13. The link member 15 is also 70 pressed or formed from sheet metal, and at the rear end thereof a bar 17 is pivotally connected therewith by means of a rivet 18. The link 15 at its rear end overlaps the bar 17, thereby providing a stop to limit the angular 75 relationship of the bar 17 with respect to the link 15, when the shoe tree is in the operative position within the shoe, as shown in Figs. 1 and 9 of the drawings.

The rivet 18 also serves as a means of pivotal attachment of a looped finger engaging piece 19, which is adapted to be engaged by the hand of the user for the purpose of inserting or removing the shoe tree with respect to the shoe, in the manner to be hereinafter 85 more fully set forth.

The bar 17 is slidably mounted in one end of a flat sleeve member 20, which is also punched and formed from sheet metal. The free end of the sleeve member 20 carries a cup 90 shaped heel piece 21, which is secured thereto by means of integral lip portions 22 of the sleeve member 20, extending through apertures in the heel piece 21, said lip portions 22 being bent over and seated in a recess 23 in 100 the central portion of the heel piece 21.

A flat spring 24 is mounted on the side of the sleeve member 20 by means of a rivet 25, the other end of this spring 24 being provided with a pin 26, which extends through one of the side walls of the sleeve 20 and is adapted to engage selectively one of a series of apertures 27 provided in the bar 17. The foregoing arrangement enables the sleeve member 20 to be longitudinally adjusted with respect 110

to the bar 17, and to be held in the adjusted position, thereby permitting the shoe tree to be used for various sizes of shoes.

In the use of the shoe tree, the toe piece 10 is first inserted in the toe portion of the shoe, and the heel piece 21 is then brought into engagement with the interior of the shoe above the heel thereof. The finger engaging piece 19 is then pushed downward until the link 15 and bar 17 occupy the positions shown in Fig. 1 of the drawings, the angular relationship being limited by the engagement of the overlapping portion of the link member 15 with the top edge of the bar 17. The link 15 and bar 17, being now off center below the line of thrust, will serve to maintain the parts in their locked positions.

It will, of course, be understood that the natural resiliency of the shoe will permit the parts to be pushed to the locked position, which will thereafter be maintained by reason of the off-center relationship of the link 15 and bar 17 and the tension which is imparted when these parts are in such positions.

If it be found that there is either not sufficient or too much tension, the sleeve member 20 which carries the heel piece 21 may be longitudinally shifted on the bar 17 by manually releasing the pin 26, which is carried by the spring 24, from engagement with one of the apertures of the bar 17, then shifting the sleeve 20 upon the bar 17 to the proper position, and then permitting the pin 26 to re-engage the proper aperture 27 of the bar 17, which will thereafter hold the sleeve 20 and heel piece 21 in the proper adjusted position with respect to the bar 17.

The looped finger piece 19 will be found to afford a convenient means for hanging up the shoes in an out of the way location, such, for example, as on a side wall, by means of a hook 28 mounted therein, as shown in Fig. 9 of the drawings.

When the shoe tree is not in use, the same may be readily folded to occupy a small space by bending the heel piece 21 inward and pushing the same into the hollow space at the end of the toe piece 10, as shown in Fig. 3 of the drawings, the finger piece 19 being bent back over the link 15.

Having thus described the nature and characteristic features of my invention, what I claim as new and desire to secure by Letters Patent, is:

1. A shoe tree comprising a toe piece shaped to the approximate form of the inside of the front end of a shoe, a link pivotally connected to the rear end of said toe piece, a bar pivotally connected to said link, a looped finger engaging piece pivotally connected to the link and bar at their point of pivotal connection, and a heel piece adjustably mounted with respect to said bar.

2. A shoe tree comprising a toe piece shaped to the approximate form of the inside of the

front end of a shoe, a link pivotally connected to the rear end of said toe piece, a bar pivotally connected to said link, a looped finger engaging piece pivotally connected to the link and bar at their point of pivotal connection, a sleeve slidably mounted on said bar, a heel piece secured to the end of said sleeve, and means for locking said sleeve in adjusted positions on said bar. 70

3. A shoe tree comprising a toe piece shaped to the approximate form of the inside of the front end of a shoe, a link pivotally connected to the rear end of said toe piece, a bar pivotally connected to said link, a looped finger engaging piece pivotally connected to the link and bar at their point of pivotal connection, a sleeve slidably mounted on said bar, a heel piece secured to the end of said sleeve, and means for locking said sleeve in adjusted positions on said bar comprising a spring 80 mounted on the side of said sleeve, a pin carried by said spring and extending through an aperture in said sleeve, and the bar being provided with a plurality of apertures adapted to be selectively engaged by the pin which is carried by the spring. 90

4. A shoe tree comprising a toe piece formed of sheet metal and shaped to the approximate form of the inside of the front end of a shoe, said toe piece having an inturned lip at the lower marginal edge thereof and being provided with a plurality of longitudinally extending slots arranged in staggered relationship, a link pivotally connected to the rear end of said toe piece, a bar pivotally connected to said link, a looped finger engaging piece pivotally connected to the link and bar at their point of pivotal connection, and a heel piece adjustably mounted with respect to said bar. 95 100

5. A shoe tree comprising a toe piece formed of sheet metal and shaped to the approximate form of the inside of the front end of a shoe, said toe piece having an inturned lip at the lower marginal edge thereof and being provided with a plurality of longitudinally extending slots arranged in staggered relationship, a link pivotally connected to the rear end of said toe piece, a bar pivotally connected to said link, a looped finger engaging piece pivotally connected to the link and bar at their point of pivotal connection, a sleeve slidably mounted on said bar, a heel piece secured to the end of said sleeve, and means for locking said sleeve in adjusted positions on said bar. 110 115 120

6. A shoe tree comprising a toe piece formed of sheet metal and shaped to the approximate form of the inside of the front end of a shoe, said toe piece having an inturned lip at the lower marginal edge thereof and being provided with a plurality of longitudinally extending slots arranged in staggered relationship, a link pivotally connected to the upper rear end of said toe piece, a bar pivotal- 125 130

ly connected to said link, a looped finger engaging piece pivotally connected to the link and bar at their point of pivotal connection, a sleeve slidably mounted on said bar, a heel piece secured to the end of said sleeve, and means for locking said sleeve in adjusted positions on said bar.

5   8. A shoe tree comprising a toe piece shaped to the approximate form of the inside of the front end of a shoe, a link pivotally connected to the rear end of said toe piece, a bar pivotally connected to said link, a sleeve slidably mounted on said bar, a heel piece secured to the end of said sleeve, and means for locking said sleeve in adjusted positions on said bar.

10   20   comprising a spring mounted on the side of said sleeve, a pin carried by said spring and extending through an aperture in said sleeve, and the bar being provided with a plurality of apertures adapted to be selectively engaged by the pin which is carried by the spring.

15   25   7. A shoe tree comprising a toe piece shaped to the approximate form of the inside of the front end of a shoe, a link pivotally connected to the rear end of said toe piece, a bar pivotally connected to said link, a sleeve slidably mounted on said bar, a heel piece secured to

the end of said sleeve, and means for locking 20
said sleeve in adjusted positions on said bar.

8. A shoe tree comprising a toe piece shaped to the approximate form of the inside of the front end of a shoe, a link pivotally connected to the rear end of said toe piece, a bar pivotally connected to said link, a sleeve slidably mounted on said bar, a heel piece secured to the end of said sleeve, and means for locking said sleeve in adjusted positions on said bar.

25   30   comprising a spring mounted on the side of said sleeve, a pin carried by said spring and extending through an aperture in said sleeve, and the bar being provided with a plurality of apertures adapted to be selectively engaged by the pin which is carried by the spring.

35   In testimony whereof, I have hereunto signed my name.

WILLIAM G. MOLAND.
